AUTOMATIC CUT-OUT

Herbert L. Brump, Dayton, Ohio, assignor, by
mesne assignments, to Radio Corporation of
America, New York, N. Y., a corporation of
Delaware

Application January 27, 1932, Serial No. 589,087

4 Claims. (Cl. 179—100.4)

This invention relates to improvements in automatic phonograph mechanism in general, but more particularly to that class of mechanism designed to successively reproduce a plurality of records and in which there is a definite cycle of movements of various contributing parts of associated mechanism. In instruments of this character, means are usually provided for lifting the pickup device and moving it from over the turn table while the latter is being charged with a new record, thence for positioning the pickup device on the face of the new record where it continues until the selection has been reproduced, whereupon a repetition of the removal of the pickup means is inaugurated which may or may not be attended with the temporary stopping of the turn table driving means. With a device of this character it frequently happens that the attendant desires to stop the reproduction of some one particular record, or cancel it and thence continue with the next record that he has selected, or for some reason desires to stop the instrument altogether. Means are usually provided in an instrument of this character for initiating the stop mechanism or for open circuiting the turn table driving means, but these means to be most efficient in the light of prior art devices are usually associated in parallel to the automatic mechanism for stopping the turn table driving means only at the completion of a certain cycle of movement, which would not ordinarily permit the attendant to immediately accomplish the result he desires, namely to silence the instrument simultaneously with the manipulation of the designated control manual.

It is therefore one of the objects of the instant invention to provide means and mechanism for an automatic reproducing instrument whereby a composition being reproduced may be silenced simultaneously with a manipulation of the control manual.

A further object of the invention is to provide means for audibly indicating to the attendant whether or not he has actually produced the result attempted when he actuates the instrument stop manual.

A further object of the invention is to silence an instrument of the character described simultaneously with the attendant's actuation with a corresponding control manual.

A further object of the invention is to provide means for instantly stopping the audible output of an automatic record changing phonograph though the record driving mechanism may continue to complete its cycle of movement.

A further object of the invention is to provide an instantaneous responsive control for automatic musical instruments.

Further objects and advantages of the present invention will be apparent from the following description, reference being had to the accompanying drawing wherein a preferred embodiment of one form of the present invention is clearly shown.

In the drawing:

Fig. 1 illustrates diagrammatically the contributing elements of an automatic record changing phonograph, with the principal circuits related thereto and as embracing the instant invention.

Fig. 2 is a fragmentary view showing the relation of the switch elements when the apparatus is to be silenced.

With particular reference to the drawing 20 indicates a turn table adapted to support and rotate one or more of a plurality of records 22, 24 and 26 and is mounted upon a shaft 28 driven by a motor or similar device 30 whose operation is wholly controlled by the automatic mechanism 32. It is preferred that the motor 30 be 25 an electric motor that is supplied with energy over the conductors 33 and 34 fitted with a detachable plug 36 making removable connection with the receptacle 38 communicating by a conductor 40 with a power source. The automatic mechanism 32 may include means for continuing the driving of the turn table 20 throughout a definite cycle of movement, and embraces mechanism for causing the periodic charging of the records 22, 24 and 26 upon the turn table, as well as means for stopping the movement of the turn table 20 at a particular foreordained point of the next cycle of operation. The means for stopping the turn table 20 usually embrace a master switch, perhaps cam operated, which switch is 40 directly or indirectly inserted in the energizing circuit of the motor 30. It is here indicated by dotted lines as embracing the contact members 35 and 37, shunted across the lead line 34. This mechanism 32 may be of the type shown and described in the patent to Beenken Patent 1,622,756, issued March 29, 1927.

Cooperable with the turn table 20, so as to respond to the particular indicia carried by each of the records, there is provided a pickup device 42 that also responds to the automatic mechanism 32. When the pickup reaches the inner ring of the record, or approaches the axis of the turn table, the pickup is caused to be moved to a remote position at one side of the table during 55

the record changing operation and is then moved for engagement with the succeeding record. The pickup device 42 is illustrated as the magnetic type, in which a stylus 44 is designed to follow the track of the record and has one element thereof disposed in the field of a coil 46 connected by leads 48 and 50 with a winding 52 of a transformer 54 whose cooperable winding 56 forms the input to a reproducing and amplifying circuit. It is the usual practice to insert in the pickup circuit a resistance 58 that cooperates with a movable contact 60 thereby constituting a volume control. The structure thus far described constitutes prior art devices and is generally well known to one experienced in the art. In the operation of such a device, once the motor 30 is started into operation the turn table will be driven to rotate the records with which it is charged, and the pickup device 42 will be moved to a position over the record whereupon it will be lowered to engage the tract of said record, which pickup device will translate the indicia of the record and through the pickup circuit with its connection to the volume control and transformer 54 will manifest in an audible rendition of the translation that has been made. This operation will continue until the pickup device has completed the translation of the record, whereupon the automatic mechanism 32 will be tripped so that the pickup device will be removed from the table and carried to one side thereof, allowing for the disposition of another record upon the table and thence the pickup device will again be moved to a position where it engages the succeeding record and so on until the entire bank of records has been reproduced.

Where it becomes desirable to stop the instrument for any reason, a manual switch inserted in the circuit of the motor 30 is actuated to open that circuit, but due to the automatic mechanism 32, the driving of the turn table 20 will not be actually stopped until the table has been driven through its predetermined cycle of movement, which is accomplished only at the time when the pickup device 42 has traversed the full length of the record groove and arrived at or near a point at the axis of the turn-table where it trips the mechanism to inaugurate the full stop of the turn-table and is thence moved to one side of the turn-table. It is thus seen that though the attendant may open the manual motor switch at some point intermediate the beginning and end of the program indicia carried by the record, the actual accomplishment of his act is delayed until the record has been fully reproduced, and thus the attendant is permitted to stop the instrument only at the conclusion of a selection that has been started.

The instant invention overcomes these objections by providing means for short circuiting the pick-up device or circuit, and that are coincidentally operable with the manually controlled switch that is inserted in the supply lead 34 to the driving motor. Diverse and several means and mechanism may be adapted to accomplish this result but for the purpose of illustration the improvement has been illustrated in the drawing as embodying a pair of spring leaf conductors 62 and 64 inserted in the lead line 34 of the motor, and which are normally under spring tension so that in their free state they will engage one another as indicated at 66, thereby completing a circuit from the motor 30 through the leads 34 to the detachable plug 36. As these contacts are

in parallel with the usual contacts to be actuated by the automatic mechanism 32, it necessitates that the motor circuit be opened at both points in order to stop operation of the driving motor. A shunt is provided in the pickup circuit so as to by-pass the volume control, or in other words to short circuit the pickup device simultaneously with the opening of the motor circuit by the manual means.

In the illustrated embodiment, a lead 68 is joined to the conductor 48 in the pickup circuit and makes communication to a leaf spring conductor 70 that is normally under spring tension and adapted to engage a co-operating leaf spring conductor 72 in electrical communication with the conductor 50 by means of a lead 74. A controller 76 is provided for actuating the spring leaf conductors inserted in both the motor circuit and the shunt to the pickup circuit, and embraces an insulating member 78 pivoted at 80 having a manual 82 for controlling the same. Upon appropriate portions of the nonconductor 78 there are provided cam rollers or similar devices 84 and 86 which when the controller is actuated will alternately engage one or the other of the spring leaf conductors 64 and 70 respectively. All of the spring leaf conductors are so associated with the controller, and so responsive to that movement, that upon actuation of the manual 82 for disengaging one pair of the conductors, the other pair of conductors will be engaged so that manipulation of the controller will amount to a simultaneous closing of one circuit in response to the opening of the other circuit and vice-versa.

As the contributing parts are illustrated in the drawing, they are figuratively descriptive of the apparatus in its operation, wherein the motor circuit is closed to provide movement of the record by which the pickup device may follow the track thereon translating the indicia thereof to electrical impulses over the pickup circuit, which by reason of the open circuit condition of the shunt will be impressed upon the transformer 54, and thence amplified through the reproducing mechanism. In the actual physical embodiment of the invention the controller 76 is provided with means for maintaining it in either of the positions to which it is movable, and since the illustration is wholly diagrammatic or at least so far as it is practical it is not deemed necessary to show the particular means necessary to hold the controller in one position or the other. It is deemed sufficiently illustrated, and is thought to be obvious that the controller 76 may be maintained in the position illustrated in Fig. 1, or if moved to the reverse position in which the contact members 62 and 64 are separated and the contacts 70 and 72 are closed as in Fig. 2, that the controller may be retained in that position.

By the structure thus provided the attendant may instantaneously silence the instrument at any point in the rendition of a particular record that he desires. To accomplish this he has naught to do but to move the controller 76 toward the right hand side of the drawing which movement will pivot the member about the point 80 flexing the conductor 64 so as to disengage it from the conductor 62 thereby opening the motor circuit. Coincident with this the spring leaf conductors 70 and 72 will be engaged which will cause the circuit pulsation from the pickup device to traverse the shunt circuit rather than the high resistance path through the volume control and the transformer winding. Presupposing that the mechanism is as has been described, the turn-table 20

and consequently the record with which it is charged will be driven throughout the predetermined cycle of movement, or until the automatic mechanism 32 operates through its cam or other means to actuate the master switch. However, directly that the controller 76 is so moved to inaugurate stopping of the device, the instrument will be silenced through the attendant's short circuiting of the pickup device. Applicant therefore 5 accomplishes the immediate silencing of the instrument directly upon manipulation of a particular control which may be at any point in the reproduction of the particular record, and is not forced to wait until a definite cycle of the automatic mechanism has been performed, or until 10 the particular record has been entirely reproduced. This becomes very desirable when the particular record is one which the attendant does not particularly care for, or in any instance where 15 it is the attendant's desire that the instrument be immediately silenced. A particular application of the latter instance is found where a telephone call is received during the performance of the instrument and it is desired that all confusion be eliminated while the telephone message is being taken. Obviously, it would be inconvenient, or undesirable to say the least, if one had to put up with the 20 complete rendition of the record before the telephone could be answered or the message taken.

25 While the form of embodiment of the present invention as herein disclosed constitutes a preferred form, it is to be understood that other forms might be adopted, all coming within the scope of the claims which follow.

30 35 What is claimed is as follows:

1. In an automatic phonograph having means for reproducing a plurality of records in succession, and having an electrically driven turn table, an electric pick-up device for translating the indicia of records carried by the table, automatic means for moving the pick-up device from the record at the conclusion of each rendition, means to charge the turn table with another record, and means to stop the driving of the turn 40 table at a predetermined point in its operation, the combination comprising, a switch in the circuit of the said electrically driven turn table, for initially open circuiting the same, a pair of contacts in parallel with the pick-up device, and means for closing the contacts in the pick-up circuit upon the initial opening of said turn table driving circuit, whereby said pick-up device becomes nonoperative upon the manipulation of 45 said closing means though the automatic means

for driving the turn table may operate throughout its predetermined cycle.

2. In an automatic phonograph having means for driving a turn table and playing a plurality of records in succession, including means for stopping the turn table at a predetermined point and only at the end of a record being reproduced, and an electric pick-up device operable to engage and translate the indicia of each succeeding record, the combination comprising a manually controlled switch in the circuit of said turn table driving means, and means for short circuiting said electric pick-up device upon the manipulation of said manually controlled switch, whereby said phonograph will be silenced coincident with 10 said manipulation yet the turn table driving means will be permitted to complete its cycle of movement.

3. In an automatic phonograph having means for driving a turn table and playing a plurality 20 of records in succession, including means for stopping the turn table at a predetermined point and only at the end of a record being reproduced, and an electric pick-up device operable to engage and translate the indicia of each succeeding 25 record, the combination comprising, manually operable stopping means in the circuit of said turn table driving means and in parallel with the turn table stopping means, a shunt across the pick-up circuit providing a pair of contacts, and 30 means responsive to the actuation of said manually operable stopping means for closing the contacts in said shunt whereby the pick-up device will be rendered nonoperative upon the initial opening of said turn table driving means. 35

4. In an automatic phonograph, the combination of a turn-table adapted to hold the record to be played, an electric motor for driving said turn-table, leads to said electric motor, a switch in one of said leads, means for opening said switch at a predetermined point in the cycle of operation of said automatic phonograph, a second switch in parallel with the first mentioned switch, an electric reproducer adapted to be operated from said record, means for short circuiting said electric reproducer, and means for simultaneously open circuiting said second switch and operating said short circuiting means to short circuit said electric reproducer, whereby said automatic phonograph is immediately silenced and said turn-table is permitted to rotate until said predetermined point in the cycle of operation of said automatic phonograph is reached. 40 45 50
